UNITED STATES PATENT OFFICE.

CARL TUTELMAN, OF PHILADELPHIA, PENNSYLVANIA.

SHIRT.

Application filed January 5, 1924. Serial No. 684,633.

To all whom it may concern:

Be it known that I, CARL TUTELMAN, a citizen of the United States, residing at Philadelphia, in the county of Philadelphia and State of Pennsylvania, have invented certain new and useful Improvements in Shirts; and I hereby declare that the following is a full, clear, and exact description thereof, reference being had to the accompanying drawings, which form part of this specification.

This invention relates to improvements in shirts, and the principal objects thereof are to provide novel means for holding the shirt down in proper position when applied to the wearer, and to prevent the tail portions from working upwardly, and to prevent the tail portions from bunching or collecting about the hips or thighs of the wearer.

I will explain the invention with reference to the accompanying drawings which illustrate one practicable embodiment thereof to enable others to adopt and use the same, and will summarize in the claims, the novel features of construction, and novel combinations of parts for which protection is desired.

In the drawings:

Fig. 1 is an extended plan view of a shirt showing my novel attachment.

Fig. 2 is a part front view of the shirt in part closed position.

Fig. 3 is a longitudinal section through the shirt in closed position.

As shown in the drawings, the shirt S, upon which my novel tape is used, may be either a top, work, or dress shirt preferably of the coat-type or style, the particular kind of coat type shirt forming no part of the present invention, said shirt comprising a back S', and sides S², S³ united to the back S' by means of side seams S⁴, S⁵. The sides S², S³ are adapted to meet in coat fashion at the front center of the wearer, and to be held together by means of buttons engaging button holes in the usual manner, or if desired any other type of fastening means may be used. The button edges of the back S' and sides S², S³, are preferably rounded or

curved as shown, in the usual manner, although said edge may be of any other desired shape.

The lower outer corners of the side portions S², S³, are preferably square, and in the lower outer corner of said side portion S² is a button 1, adapted to engage a button hole 1^a in the lower outer corner of the opposite side portion S³ when the portions S², S³ are brought together in coat fashion.

A tape 2, preferably continuous, is provided on the under side of the shirt adjacent the lower edge thereof, said tape comprising a member 2^a extending diagonally upwardly across the side portion S², from the button 1 to the lower extremity of the seam S².

A second tape member 2^b extends diagonally downwardly from the inner end of member 2^a, at the seam S⁴, to the lower edge of the back S' at the center thereof.

A third tape member 2^c extends diagonally upwardly symmetrically with tape 2^b, from the lower edge of back S' at the center thereof to the lower extremity of side seam S⁵.

A fourth tape member 2^d, symmetrical with tape 2^a, extends diagonally downwardly from the adjacent end of tape 2^c, at the seam S⁵, and terminates at the button hole 1^a. All tape members 2^a, 2^b, 2^c and 2^d are preferably about three-fourths of an inch less in length than the length of material between their respective ends, for the purpose hereinafter specified. If desired, the members 2^a, 2^b, 2^c, and 2^d could all be made separately instead of being integral with the tape 2.

A crotch tape 3, depends from the center of the back S', as shown, said tape 3 being sewed to the back of the shirt and to the adjacent ends of tape members 2^b, 2^c. Tape 3 is preferably about nine inches in length, and the outer end of tape 3 is provided with a plurality of button holes 3^a, any one of which holes 3^a is adapted to be engaged by the button 1, when the shirt is applied to the wearer, strap 3 being passed under the crotch of the wearer, and upwardly to meet the front of the shirt, in order that button

hole 3^a may be engaged by button 1. The plurality of holes 3^a provide an adjustable crotch tape 3, as shown.

Since the tape members 2^a, 2^b, 2^c and 2^d are each shorter than the length of shirt material between their respective ends, when the shirt is applied to the wearer, and the crotch strap 3 fastened to button 1, as above described, the tape members will take up the tension in the shirt material exerted by the crotch strap 3, said tape members tending to hold the shirt down at the front sides and back and members 2^a, 2^b, 2^c, 2^d further preventing the material of the shirt from collecting or bunching at the hips or thighs of the wearer, as is experienced by the wearer with shirts not provided with means for preventing same. The tape members tend to fit closely to the body of the wearer and the difference between the lengths of the said tape members and the lengths of the shirt material between the respective ends of each tape member, permits the desired fullness of the shirt material between the ends of each tape, but prevents bunching of the shirt material at any portion of the waist of the shirt.

By my novel attachment, the shirt is held down by fastening the single button 1, which fastens the lower corners of the sides S², S³ of the shirt together, and likewise connects the crotch tape 3 attached to back S' to the lower edge of the front of said shirt.

The tape members 2^a, 2^b, 2^c and 2^d relieve the strain on the shirt material itself when applied to the wearer, and also relieve the strain of the material around the connection of the crotch strap 3 to the back S' of the shirt.

I do not limit my invention to the exact construction shown in the drawings, for obviously changes could be made in the details of the construction without departing from the scope of the invention.

I claim:

1. In combination with a coat type shirt, a tape attached to the lower outer corners and at intervals along the lower edge of said shirt; said tape being of less length than the length of the lower edge of said shirt; means for fastening the lower corners of said shirt together; and a crotch strap extending from the center of the back of said shirt and adapted to be attached to said fastening means at the front of the shirt.

2. In combination with a coat type shirt, a tape attached to the lower outer corners and at intervals along the lower edge of said shirt; said tape being of less length than the lower edge of said shirt; means for fastening the lower corners of said shirt together; a crotch strap extending from the center of the back of said shirt and adapted to be attached to said fastening means at the front

of said shirt; and means for varying the effective length of said strap.

3. In combination with a coat type shirt, a tape extending along the under side of said shirt adjacent the lower edge thereof; the ends of said tape being attached to the lower outer corners of said shirt, and the center of said tape being attached to the lower edge of the shirt back at the center thereof, and said tape being attached to one intermediate point between each outer corner and the center of the back; said tape being of less length than the length of the lower edge of said shirt; means for fastening the said lower outer corners of said shirt together; and a crotch strap depending from the center of the shirt back and adapted to be attached to said fastening means at the front of said shirt.

4. In combination with a coat type shirt, a continuous tape extending along the lower edge of said shirt on the under side thereof; the outer ends of said tape being attached to the lower outer corners of said shirt, and the center of said tape being attached to the center of the back of said shirt at the lower edge thereof, and said tape being attached at an intermediate point on each side of the shirt, said points of intermediate attachment being above the plane of the end and center points of attachment; said tape being of less length than the length of the lower edge of said shirt; a button for fastening the said lower outer corners of said shirt together; and a crotch strap depending from the center of the shirt back and adapted to be fastened to said button at the front of said shirt; and means for adjusting the effective length of said strap.

5. In combination with a coat-type shirt having a back portion, and side portions connected to said back portion by vertical seams; a tape extending along the lower edge of said shirt, said tape being attached to the shirt at the outer lower corners of the side portions and at the center of the lower edge of the back portion and at the lower ends of said seams respectively; said tape being of less length than the lower edge of said shirt; a button at one lower corner adapted to engage a button hole at the other lower corner of side portions of the shirt; and a vertically depending crotch strap attached to the center back of said shirt and adapted to be passed upwardly under the crotch of said wearer; and to be fastened to said button.

6. In combination with a coat-type shirt having a back portion, and side portions connected to said back portion by vertical seams, a continuous tape extending around the under side of said shirt adjacent the lower edge thereof; said tape being attached to the shirt at the outer lower corners of the side portions, and at the center of the back at

the lower edge, and at the lower ends of said side seams respectively; said tape being of less length than the length of the lower edge of said shirt; a button at one lower corner adapted to engage a button hole at the other lower corner of side portions of the shirt when said shirt is applied to the wearer; a crotch strap depending from the center back of said shirt, and adapted to be passed upwardly under the crotch of said wearer and to be fastened to said button; and a plurality of button holes in said strap for adjusting the effective length thereof.

In testimony that I claim the foregoing as my own, I affix my signature.

CARL TUTELMAN.
